DESIGN FOR A BOTTLE

John Akinori Oya and Roy Albert Larson, Honolulu, Territory of Hawaii, assignors to Hollister Drug Company, Ltd., Honolulu, Territory of Hawaii, a corporation of Hawaii

Application November 25, 1936, Serial No. 66,144

Term of patent 14 years

To all whom it may concern:

Be it known that we, John Akinori Oya and Roy Albert Larson, citizens of the United States, and residents of Honolulu, Territory of Hawaii, have invented a new, original, and ornamental Design for a Bottle, of which the following is a specification, reference being had to the accompanying drawing, forming a part thereof.

We claim:

The ornamental design for a bottle substantially as shown.

JOHN AKINORI OYA.
ROY ALBERT LARSON.
